UNITED STATES PATENT OFFICE.

WALTER A. STEARNS, OF CHICAGO, ILLINOIS, ASSIGNOR TO AMERICAN STEEL
FOUNDRIES, OF NEW YORK, N. Y., A CORPORATION OF NEW JERSEY.

CAR-UNDERFRAME.

1,079,958.

Specification of Letters Patent.

Patented Dec. 2, 1913.

Application filed May 23, 1913. Serial No. 769,374.

To all whom it may concern:

Be it known that I, WALTER A. STEARNS, a citizen of the United States, and resident of Chicago, in the county of Cook and State 5 of Illinois, have invented certain new and useful Improvements in Car-Underframes, of which the following is a specification.

My invention relates to railroad cars and has particular reference to a novel means 10 for strengthening the center sills and providing adequate shock absorbing facilities whereby the blows sustained under buffing are transmitted to the car body.

A very great number of cars have heretofore been built with wooden underframing, particularly wooden center sills and such cars are constantly being built it being much cheaper to construct cars in such manner than to provide an underframe of fabricated steel. 15 However, it is found in practice that due to the excessive shocks of buffing these wooden center sills become broken at the ends and further, that they will not hold the bolts by means of which the draft sills are attached thereto. I propose to suitably reinforce the wooden center sills of such cars by means of a cast steel strengthening member which shall extend to a point to the rear of the body bolster. I have found that 20 much of the destruction and fracture of the center sills occurs at the ends between the body bolster and the end sill. I propose therefore to terminate the center sills at a point just ahead of the body bolster abutting the ends of the sills against shoulders forming part of the reinforcing castings, these shoulders forming also a portion of the rear stops for the draft rigging. By 25 this construction I have found that buffing shocks are applied directly to the ends of the sills, there is no tendency to dislocation of the fastening bolts and the shock is more evenly distributed to the frame members and the body bolster.

I am aware that the idea of strengthening wooden center sills by means of a reinforcing structure which shall extend to the rear of the body bolster is not new having been heretofore shown in the patent to 30 Crawford, No. 915,272.

My invention will be more readily understood by reference to the accompanying drawings, wherein,

Figure 1 is a plan view showing a pair of 35 reinforcing members secured to wooden cen-

ter sills and coöperating with a wooden end sill and a metallic body bolster; Fig. 2 is a side elevation of one of the reinforcing members; Fig. 3 is an end view; Fig. 4 is a transverse section on the line 4—4 of 60 Fig. 1, and Fig. 5 is a similar section on the line 5—5 of Fig. 1, the body bolster being omitted.

Referring more particularly to the drawings, it will be seen that my novel reinforcing member is composed of an integral casting having a rearwardly extending vertical web 10, and a horizontal web 11, these webs being arranged at right angles and providing an elongated pocket within which a 70 wooden center sill 12, is accommodated. At the front end of the webs 10, 11, a shoulder 13 is formed this shoulder providing an abutment against which the end of the center sill 12 may rest. This shoulder 13 also 75 provides a stop 14, for a draft rigging follower. It will be noted by this construction that excessive buffing shocks are transmitted direct from the rear follower to the reinforcing member and thus directly to the 80 ends of the center sills. Projecting downward from the web 11 are ribs 15, providing a wide groove within which the lower portion 16 of a body bolster can be accommodated.

Extending forward from the abutment 13, the reinforcing member takes the form of the draft rigging cheek plates and consists of a vertical web 17, having horizontal flanges 18, and provided with notches 19, 90 within which the draft rigging followers are accommodated. The configuration of this portion of the reinforcing member will correspond to the type of draft rigging to be employed and may vary widely.

The forward end of the reinforcing member is terminated in an abutment 20, for an end sill. Projecting beneath this end sill is an integral shelf 21, on which the end sill rests and through which fastening bolts 22 100 may extend. In order to suitably strengthen the end sill at the point of connection I have provided a strengthening plate 23, which extends above the end sill and overlies the reinforcing members at a point considerably 105 to the rear of the end sill. This member 23 is suitably bolted through the end sill but is securely riveted by three rivets to each of the reinforcing members.

Secured to the front face of the end sill I 110

provide a cast buffer block 24, which differs somewhat from the blocks heretofore employed in that it extends laterally to a point where it may accommodate the tightening nuts 25, for the longitudinal truss rods of the car. These rods are shown in Figs. 3 and 4. This buffer casting is also provided with a horizontally extending shelf 26, on each side of the line of draft, this shelf acting as a strengthening member, and also as a support for an angular carry iron 27. The fastening bolts for the carry iron extend through openings in the shelf 26.

The construction described is commonly applied to the center sills by means of bolts as shown. The reinforcements are usually applied as repairs and in such case the end sill is removed, the center sills are sawed off and the reinforcing members applied.

It is obvious that modifications may be made in the construction shown and such modifications as are within the scope of my claims I consider within the spirit of my invention.

I claim:

1. In underframing for railway cars, the combination of center sills terminated at a

point between the end sill and body bolster, and a combined center sill reinforcing member and draft sill applied to said center sills, 30 said reinforcing member having a portion extending to the rear of the body bolster and having a squared shoulder against which the end of the center sill may abut whereby buffing force is applied directly to the ends of 35 said center sills, substantially as described.

2. In underframing for railway cars, the combination of center sills terminated at a point between the end sill and body bolster, and combined center sill reinforcing members and draft sills applied to said center sills, 40 said reinforcing members embracing said center sills on both sides of said body bolster and each being provided with a transverse shoulder against which the end of a 45 shortened center sill may abut, whereby buffing force is applied in a direct line against the ends of said center sills, substantially as described.

WALTER A. STEARNS.
